BOWLING BALL GRIP-MEASURING DEVICE

Robert S. Fleming, Pompton Plains, N.J., assignor to Amerace Corporation, New York, N.Y., a corporation of Delaware

Application December 24, 1957, Serial No. 704,916

5 Claims. (Cl. 33—174)

The present invention relates to a bowling ball grip-measuring device, and more particularly to a device which, in its assembled and operative arrangement, simulates a standard bowling ball and yet which has a plurality of separate and relative adjustable parts so arranged that different combinations of thumb and finger holes may be positioned in various relations to each other, so that a person seeking to purchase a bowling ball and to have it drilled to accommodate that particular person's hand, may experiment with an almost infinite number of combinations of sizes and relative positions of finger and thumb holes so as to ascertain exactly what relationship and combination of these holes are desired for his or her own personalized bowling ball.

As such, the present invention is an improvement upon the "Hand Measuring Device" set out in the patent to Jast et al. No. 2,703,934 issued March 15, 1955. In this patented device, as in the present application, there is a three-part or three-section-type apparatus simulating a bowling ball, the outer two sections of which comprise segments of spheres. One of these segments has a plurality of different size thumb holes therein and the other a plurality of pairs of different size finger holes therein. These two thumb and finger hole-provided spherical segments may be relatively adjusted with respect to each other and with respect to a third or central section which is so constructed and arranged that the outer spherical segments may be adjustable with respect thereto about axes which are at an angle to each other, so that the spacing between finger and thumb holes, even after the size of each has been selected, may be varied as desired to accommodate all possible spacings which are usable in practice.

In the patented device aforesaid a separate securing means is used for securing the center wedge-shaped section to each of the outer or spherical segment sections respectively, so that there are two separate and distinct locking means used in this device.

The present invention has for its object to provide a simpler embodiment of the device disclosed in the Jast et al. patent, in that the central section is made hollow, as in a split ring, having a substantially spherical outer contour; and means are provided for so securing the ends of the split ring with respect to each other that this split ring, which has interengaging flange portions with each of the other portions or sections, will be caused to engage and lock with respect to both outer sections by a single locking means. This single locking means in the present embodiment of this invention is preferably arranged to be disposed, at least in its locked position, in a suitable recess accessible from the outside, so that the device as a whole, when in an operative position, has a substantially uninterrupted spherical outer contour and could, if desired, be actually used as a bowling ball and bowled on a conventional bowling alley.

Other and more detailed objects of the present invention will become apparent from the following descrip-

tion of a preferred embodiment thereof, which is illustrated in the accompanying drawings, in which:

Fig. 1 is a view in elevation, showing the entire device in an assembled and operative position;

5 Fig. 2 is a fragmentary sectional view of the device, taken substantially on the line 2—2 of Fig. 1;

Fig. 3 is a fragmentary sectional view illustrating particularly the single locking means for the device and taken substantially on the line 3—3 of Fig. 1, with the locking means in its locked or operative position; and

10 Fig. 4 is a fragmentary sectional view similar to Fig. 3, but with the locking means in its released position.

Turning now to the accompanying drawings, the device of the present invention includes a substantially spherical segment section 10 having a plurality of different size thumb holes 11 therein and a substantially similar spherical segment section 12 having a plurality of pairs of different size finger holes 13 therein. A third or central section generally indicated at 14, which is arranged with locking means hereinafter described, completes the overall combination of the device. Each of the outer sections 10 and 12 has a spherical outer contour and also has an annular (circular) groove 15 adjacent to the peripheral edge of the spherical surface thereof. The central section 14 is shown provided with a pair of flanges 16 interengaging with the groove 15 as shown. From another point of view, it may be said that the outer sections 10 and 12 are provided with flange portions shown at 17 bounding the grooves 15 and interengaging with the flanges 16. The inner surfaces of the outer sections 10 and 12 may be formed as shown as planiform surfaces 18 and 19. However, the shape or conformation of these inner surfaces is of no import, as it is necessary merely that they will not engage with one another and that they will not interfere with the substantially free adjustive movement between each of the outer sections 10 and 12 respectively and the central section 14.

40 The central section 14 is formed as shown substantially as a split ring with the ends thereof spaced apart by a predetermined relatively small distance as shown at 20. In the form of the invention shown, when the central section 14 is unlocked as hereinafter set out, it will be sufficiently free and the gap or space 20 sufficiently wide so that each of the outer sections 10 and 12 may be freely rotatably adjusted with respect to the central section 14. At the same time, the interlock between the flanges 16 and 17, or in other words, the depth of the grooves 15 with respect to the depth of the flanges 16, is sufficient, so that even when the central section 14 is 45 at its usual unlocked position (Fig. 4), inadvertent bodily disassembly as between the central section 14 and the outer sections 10 and 12 will be prevented, even though the outer sections are freely rotatably adjustable with respect to the central section 14 under these circumstances.

50 In the embodiment of the invention shown, with the central section 14 embracing portions of the outer sections 10 and 12, the tightening together of the open ends of the central section will be effective to lock this central section simultaneously to both outer sections. For this purpose, the central section is formed near its ends with recesses 21 and 22, and those ends, formed with walls 23 and 24, which are generally parallel to one another and in part bound these recesses respectively. The walls 23 and 24 are provided with aligned apertures, through which a bolt 25 extends, this bolt being provided as shown with a pair of lock nuts 26 on its right hand end (as seen in Figs. 3 and 4) and being provided at its left hand end with a cam lever 27 pivoted thereto at 28 and having a cam surface 29 of such form that it will in effect provide an over-center-throw

locking means as between the unlocked position of the parts shown in Fig. 4 and the locked position of the parts shown in Fig. 3. There is also shown in these figures a washer 30 between the lock nuts and the wall 23 and a washer 31 between the wall 24 and the cam surface 29 at the end of the lever 27. The washer 31 acts as an abutment against which the cam surface 29 engages in locking the open ends of the central section 14 together. It is further to be noted that at the locked position at the parts shown in Fig. 3, the lever 27 is located completely within the recess 22, so as not to interfere with or interrupt the spherical outer contour of the device as a whole.

It is contemplated, for example, that other types of interengaging flange means may be employed in the construction of the central section 14 and the outer sections 10 and 12 and that such other interengaging flange means should be considered within the purview of the present invention. Furthermore, it is contemplated that a bolt-like element, equivalent to the bolt 25, could be secured rigidly in one of the abutting ends of the split ring-type central section 14, eliminating the necessity of using the lock nuts 26 as well as eliminating the requirement for a wall as 23 and a recess as 21. Under such circumstances the parts could be assembled in a suitable way, for example, by threading a bolt-like element, equivalent to the bolt 25, into a threaded opening formed in a part of the central section 14 itself corresponding in position to the wall 23.

In any event, there is provided, according to the present invention, a single and relatively simple locking means for simultaneously causing the central section to lock with the two outer sections and for securing any adjustment as made.

In practice it may be found convenient to number the thumb holes and the several pairs of finger holes and further to provide graduations, preferably suitably numbered, around the periphery of the central section 14. Inasmuch as all such means are considered to be obvious to those skilled in the art, as they form per se no necessary part of the present invention, they have not been illustrated in the accompanying drawings.

While there is herein shown and described but one particular embodiment of the invention and equivalents of various features thereof have been pointed out as the description proceeded, other equivalents will suggest themselves to those skilled in the art from the foregoing disclosure. I do not wish to be limited, therefore, except by the scope of the appended claims, which are to be construed validly as broadly as the state of the prior art permits.

What is claimed is:

1. A bowling ball grip-measuring device, comprising two outer sections and a central section, which when assembled together make up a substantially spherical body simulating a standard bowling ball; each of said outer sections having a substantially spherical surface and a substantially planiform surface, and said central section being so shaped with a spherical portion of varying widths that the planiform surfaces of said outer sections are at an angle to one another when all said sections are assembled together; one of said outer sections having a plurality of different size thumb holes therein, the other of said outer sections having a plurality of pairs of different size finger holes therein; said central section being substantially hollow and being formed substantially as a split ring with ends spaced a short distance apart, a peripheral groove portion formed on each of said outer sections adjacent to the boundary between the spherical and planiform surfaces thereof, a pair of interlocking flange portions formed on said central section, the in-

terlocking flange portions of said central section engaging the peripheral groove portions of said outer sections respectively and so constructed and arranged that when said central portion is at its loosened position, each of said outer sections may be independently rotatively adjusted with respect thereto; and a single means for simultaneously clamping said ends of said central section together and thereby causing said flange portions thereof tightly to grip both said outer sections, so as to hold all three sections of said device in any adjusted position.

2. A bowling ball grip-measuring device according to claim 1, in which said single means for clamping the ends of said central section together comprises a bolt extending through an aperture in a flange portion of one of said ends, and means carried by said bolt for urging said ends together and for holding them in a locked operative position of the device; and in which said central section is provided with at least one recess in which said means carried by said bolt is located in said locked operative position of the device, so as not to extend through the spherical outer contour of the device at said operative position of the parts thereof.

3. A bowling ball grip-measuring device according to claim 2, in which said means carried by said bolt comprises a cam lever pivoted to said bolt and effective by an over-center-throw action accompanying its movement into said recess to lock all the sections of said device in said operative position.

4. A bowling ball grip measuring device, comprising two outer sections and a central section, which when assembled together in an operative position, make up a substantially spherical body simulating a standard bowling ball; each of said outer sections having an outer spherical surface portion and an annular flange portion bounding said spherical portion, one of said outer sections having a plurality of different size thumb holes therein, and the other of said outer sections having a plurality of pairs of different size finger holes therein; said central section being formed as a hollow shell, split to provide two ends which are spaced a short distance from each other, said central section further having flange portions shaped to interfit with said annular flange portions of said outer sections respectively and to grip said outer sections, so as to prevent relative movement therebetween when said central section is forced to its locked and operative position, the flange portions of said central section lying in planes which are non-parallel and at a predetermined angle to each other in the operative position of all said sections; and a single locking means interengaging with the ends of said central section for flexing it and forcing it to its locked and operative position and so as to cause the flange portions thereof to grip both said outer sections in any adjusted position of such outer sections respectively, said outer sections being independently rotatably adjustable with respect to said central section when said locking means is not at its locking position as aforesaid.

5. A bowling ball grip-measuring device in accordance with claim 4, in which said flange portions of said central section interfit with said annular flange portions of said outer sections to an extent sufficient, even during the positions of the parts when said locking means is at its unlocked position, that inadvertent bodily disassembly as between said central section and said outer sections respectively will not occur, but relative rotative adjustive movement therebetween is freely permitted.
